ELECTRIC REGULATOR

Frederick Newton, Derby, England, assignor to
 Newton Brothers (Derby) Limited, Derby, Eng-
 land

Application March 24, 1942, Serial No. 436,049

13 Claims. (Cl. 201—51)

This invention relates to electric regulators and more particularly has reference to a carbon pile regulator suitable for use under extraordinary conditions.

Carbon pile regulators have been found very desirable for use in controlling the electrical systems of airplanes and other means of transportation. Regulators of the carbon pile type operate effectively under all normal and even most abnormal conditions of airplane flight. However, under extreme flight conditions such as exist during power dives considerable vibration occurs and if the direction of vibration is parallel to the axis of the carbon pile, it may be possible that there will be a tendency for the vibration to effect separation of adjacent discs within the pile when the compressive force applied to the pile is low. The separation of the discs due to such conditions is very detrimental because of the sparking which takes place thereon.

An object of this invention is to avoid the disadvantages in carbon pile regulators as pointed out above.

Another object of this invention is to provide a carbon pile regulator having means for avoiding the separation of adjacent discs of the carbon pile due to vibratory action while there is current flowing through the pile.

Still another object of this invention is to provide a carbon pile regulator in which separable contacts formed of a material capable of withstanding a certain amount of arcing are provided between the terminal discs of the carbon pile and the elements exerting pressure on said terminal discs.

A further object of this invention is to provide a carbon pile regulator in which separable contacts are provided between the terminal discs of the carbon pile and the elements exerting pressure on said terminal discs and in which the separable contacts are formed of material capable of withstanding a certain amount of arcing.

A still further object of this invention is to provide a carbon pile regulator suitable for use in installations in which vibratory forces exist longitudinally of the axis of the carbon pile and in which means having pairs of separable contacts are provided engaging each end of the carbon pile which contacts are more easily separable than are the adjacent discs of the carbon pile.

Yet another object of the present invention is to provide a carbon pile regulator provided with means whereby even when subjected to violent vibrations the regulator will operate normally until the carbon pile resistance is such as to re-

duce the current to within a value that can be accommodated by the usual contact forming material beyond which resistance the apparatus operates as a vibratory or "Tirrill" type regulator.

5 With these and other objects in view as will appear more fully hereinafter, the present invention comprises the parts and combinations shown in the drawing and set forth in the following description.

10 In the drawing the single figure is a more or less diagrammatic sectional view of a carbon pile regulator constructed in accordance with the present invention.

In carbon pile resistances such as employed in 15 regulators of the type set forth in my Patent No. 2,268,718, granted January 6, 1942, the resistance varies substantially inversely as the pressure applied to the carbon pile.

If such a carbon pile is subjected to vibrations 20 in line with its axis the minimum pressure (which corresponds to the highest limit of resistance) to obviate separation of the discs must be of the order of the mass weight of the pile multiplied by the acceleration involved in the vibration mass.

If a carbon pile weighs approximately .0235 25 pound and is subjected to a vibration in line with the axis of the pile approximately equal to a value of 10 G. the minimum weight on the pile to maintain the discs in contact with each other and prevent separation thereof should not be less than .235 pound.

If it be assumed that the resistance of such a 30 carbon pile when the pressure exerted thereon is at a minimum would be 60 ohms and it was desired to reduce the value of this resistance to 0.5 ohm, it would be necessary to increase the minimum pressure exerted on the pile in a ratio of 120:1, that is in the particular instance involved where the pressure on the pile should be not less than .235 pound, the minimum pressure must be approximately 28 pounds at the beginning of operation of the carbon pile in a controller installation.

45 In regulators of the type referred to in my above-described patent the pressure on the carbon pile is exerted by a spring and to reduce this pressure the spring force is opposed by an electromagnetic force. The difference of these two forces acts on the carbon pile to give it a desired resistance value.

Now if it further be considered that the regulator including the carbon pile referred to above must be accurate within $\pm 2\%$ the 28 pounds pressure must be substantially only 8% of the

counterbalancing forces present in the magnet and spring system for controlling the pressure on the carbon pile. Under such conditions the equilibrium force required would be 350 pounds. Obviously this is not practical especially in aeronautical installations where the weight and bulk of a regulator capable of producing and sustaining such opposing forces would be too great.

The extreme unusual or emergency conditions set forth above will exist in aeronautical installations only on rare occasions and then for very short periods of time, one particular instance of the existence of such conditions taking place in power dives with no load on the generator.

In accordance with the present invention it has been found that a carbon pile may be so assembled in a regulator of the type set forth in my above-mentioned patent that it will be unnecessary to have extremely high equilibrium forces present in the magnet and spring system to prevent separation of the elements of the pile under the extreme emergency conditions. This is accomplished by providing means for converting the carbon pile regulator, when such extreme unusual operating conditions exist, into a vibratory or so-called "Tirill" type of regulator. The conversion from the "Tirill" type regulator back to the carbon pile type of regulator takes place immediately the extreme emergency conditions terminate.

A carbon pile capable of accomplishing the results pointed out hereinbefore and convertible from the carbon pile type of regulator to the "Tirill" type regulator and back again is shown in the drawing.

As shown in the drawing, the controller comprises a carbon pile 1 consisting of a plurality of discs mounted in a ceramic tube 2 which in turn is positioned in the boss 3 of the frame 4. A fixed terminal 5 is mounted at one end of the carbon pile and is anchored to the frame 4 through suitable insulating material. A movable assemblage 6 is at the other end of the carbon pile and is attached to the armature 7 of an electromagnet as will be hereinafter described.

Frame 4 has a skirt-like portion 8 in which a series of circumferentially spaced bosses 9 are provided and through which bolts 10 extend.

By means of bolts 10 the frame 4 is attached to the flange 11 of the housing 12 of electromagnet 13, spacers 13a serving to maintain the housing 12 and frame 4 in proper spaced relation.

Secured to one end of housing 12 is a plate 14 in which the core 15 is threadedly mounted. Flange 16 extends inwardly from the other end of the housing 12 to a point adjacent the free end of the core and cooperates therewith to form pole pieces for attraction of the armature 7.

An annular abutment 17 is positioned against the flange 11 and mounted thereon is a bimetallic ring 18 of somewhat conical formation the conicity of which varies with the temperature. Resting on the conical bimetal ring 18 are the ends of a spring or series of springs 19 which wrap upon the ring 18 as an abutment as the spring is stressed.

The spring member 19 is secured to the armature 7 by screws 20. A terminal 21 and the assemblage 6 are attached to but insulated from the armature 7 and spring member.

Suitable insulating plates are positioned between parts of the armature-spring assembly.

On the upper end of the carbon pile there is positioned a disc 22 of metal or other suitable conductive material on which is provided a con-

tact point 23 of silver, or other suitable material generally employed for electrical contacts. Contact point 23 is located at the center of the carbon pile.

5 Cooperating with the contact point 23 is a contact point 24 carried by the end of a screw 25 threadedly mounted in the member 5. A lock nut 26 is provided to maintain the screw 25 fixed.

In contact with the carbon element at the 10 lower end of the pile is a disc 27 of silver or other suitable contact forming conductive material. Engaging this disc is a cup-shaped contact 28 the contact surface of which is annular and substantially concentric with the axis of the carbon pile. This cup-shaped contact member is carried by the assemblage 6 and has openings 29 formed therein to avoid pneumatic adherence between the same and the disc 27.

15 The peripheral portion of the cup-shaped contact member 28 is arranged concentrically with the axis of the carbon pile and the contact point 23 is arranged substantially coaxially with the carbon pile axis. With such construction the zone of pressure exerted on the carbon pile will be substantially conical and will avoid any tendency to cause buckling of the pile.

20 If a carbon pile constructed as above described is utilized as a controller in the electrical system of an airplane, for instance, and the plane, for

example, is in a power dive the generator will be 25 driven at its highest speed and in all probability the carbon pile will be extended as far as possible in order to increase its resistance. Under these conditions the carbon pile may be subjected to

30 excessive vibration and if the direction of the 35 vibration is longitudinally of the carbon pile there would ordinarily be a considerable tendency for the carbon elements of the pile to separate from each other with the consequent disadvantages 40 pointed out hereinbefore. However, with the construction of the present invention as described instead of the elements of the carbon pile separating from each other the separation will take place between the contact points 23 and 24 on

45 one hand and between the disc 27 and cup-shaped contact member 28 on the other hand. There will be a certain amount of pneumatic adherence between the discs or elements of the 50 carbon pile which will not be so in the case of the contact elements. Consequently instead of 55 elements of the carbon pile separating, the carbon pile will remain intact and any separation will occur at the contacts provided for this purpose.

56 Now it so happens that when the carbon pile 60 is extended to provide a high resistance the current flowing through the pile will be relatively low and in all probability much below 1½ amperes which can be handled fairly easily by the 65 contact points 23 and 24 and the contact occurring between the disc 27 and the cup-shaped member 28 especially if they are constructed of the conventional materials commonly used for this purpose, i. e., silver, platinum, tungsten and various alloys.

Obviously when the circuit through the carbon pile is broken by reason of the separation of the contact elements provided for this purpose the flow of current will be temporarily disrupted.

70 However, since the frequency of the vibrations will probably be high, the break will be instantaneous and the circuit will be shortly re-established. Actually under the conditions described, 75 the device will act as a vibratory or "Tirill"

type regulator during the conditions of excessive vibration.

Since the equipment will be operated under conditions producing extreme vibrations for such a comparatively short period of time and for such infrequent intervals, the normal operation of the carbon pile will be very little disrupted. Furthermore, since the operation of the device as a vibratory or "Tirrill" type regulator will prevent any damage to the electrical system during the extreme emergency conditions the electrical system of the equipment will be fully protected at all times.

The present invention contemplates the provision of means to protect the separable contacts according to any of the usual methods such as shunting a resistance, capacitance, a rectifier or combination of these across the separable contacts. It is found that with proper normal adjustment the changeover from carbon pile control to carbon pile plus vibratory contact control can take place without appreciable change in the voltage of the circuit controlled.

Having described my invention, I claim:

1. An electric regulator comprising a carbon pile included in a circuit to be regulated, means for exerting a pressure on said pile to vary the resistance thereof, and means having separable contacts also included in said circuit and interposed between the ends of the carbon pile and the means for exerting a pressure on the pile, the separable contacts being more easily separable than the elements of the carbon pile and being mounted to vibrate like the vibratory contacts of a Tirrill type regulator in response to external vibrations acting axially of the carbon pile.

2. An electric regulator comprising a carbon pile included in a circuit to be regulated, means for exerting and varying a pressure on said pile in response to characteristics of an electric current in said circuit, and means responsive to vibrations longitudinally of the pile and just short of an intensity sufficient to separate the elements of the carbon pile under the pressure exerted thereon for vibrationally breaking and remaking the circuit through the carbon pile while the vibrations continue.

3. An electric regulator comprising a carbon pile included in a circuit to be regulated, means for exerting a pressure on said pile to vary the resistance thereof, and means having separable contacts also included in said circuit and associated with elements of the carbon pile, the separable contacts being more easily separable than the elements of the carbon pile and being mounted to vibrate like the vibratory contacts of a Tirrill type regulator in response to external vibrations acting axially of the carbon pile.

4. An electric regulator comprising a carbon pile included in a circuit to be regulated, fixed means engaging one end of said pile, means responsive to a variable pressure for engaging the other end of said pile, and means having separable contacts also included in said circuit and interposed between the fixed means and the end of the pile which it engages and between the means for exerting a pressure on the pile and its associated end of the pile, the separable contacts being more easily separable than the elements of the carbon pile and being mounted to vibrate like the vibratory contacts of a Tirrill type regulator in response to external vibrations acting axially of the carbon pile.

5. An electric regulator comprising a carbon

pile included in a circuit to be regulated, fixed means engaging one end of said pile, means responsive to the differential action of a spring and an electromagnet for exerting pressure on the other end of the pile, and means having separable contacts also included in said circuit and interposed between the ends of the carbon pile and the means in engagement therewith and being mounted to vibrate like the vibratory contacts of a Tirrill type regulator in response to external vibrations acting axially of the carbon pile.

6. An electric regulator comprising a carbon pile included in a circuit to be regulated and an abutment adjacent one end of said pile, means having separable contacts also included in said circuit and interposed between the abutment and the adjacent end of the pile, a differential spring and magnet system exerting pressure on said pile and positioned adjacent the other end of the pile, and means having separable contacts interposed between said other end of the pile and the differential spring and magnet system, the separable contacts being more easily separable than the elements of the carbon pile and being mounted to vibrate like the vibratory contacts of a Tirrill type regulator in response to external vibrations acting axially of the carbon pile.

7. An electric regulator comprising a carbon pile included in a circuit to be regulated and an abutment positioned adjacent one end of the pile, means having separable contacts also included in said circuit and interposed between the abutment and said end of the pile, said separable contacts being positioned axially of the pile, means for exerting the pressure on the other end of the pile, and means having separable contacts also included in said circuit and interposed between the pressure exerting means and the corresponding end of the pile, said last-mentioned separable contacts being of annular formation and positioned concentrically of the axis of said pile, both said separable contacts being arranged to vibrate like the vibratory contacts of a Tirrill type regulator in response to external vibrations acting axially of the carbon pile.

8. An automatic electric regulator comprising a carbon pile, arc-resisting cooperating contacts one of them electrically connected with one end of the pile, and an electromagnet and spring acting in opposition to exert variable pressure upon said contacts and solely through them on the pile.

9. An automatic electric regulator comprising a carbon pile, terminals for connecting said pile to an external circuit, arc-resisting cooperating contacts included in series between said pile and said terminals, and an electromagnet and spring acting in opposition to exert variable resistance-determining pressure upon said contacts and through them on the pile.

10. An automatic electric regulator comprising an electromagnet, an abutment and a fixed contact secured to said electromagnet, an armature adjacent to said electromagnet, a spring resting and wrapping on said abutment and secured to said armature opposing the pull of the electromagnet upon it, a moving contact carried by said armature, and a carbon pile having contact-making end plates located between said fixed and moving contacts and receiving through them the resistance-determining pressure of said spring.

11. An automatic electric regulator comprising an electromagnet, an abutment and a fixed contact secured to said electromagnet, an armature adjacent to said electromagnet, a spring resting

and wrapping on said abutment and secured to said armature opposing the pull of the electromagnet upon it, a moving contact carried by said armature, a carbon pile having contact-making end plates located between said fixed and moving contacts and receiving through them the resistance-determining pressure of said spring, and terminals for connecting the regulator to a circuit to be regulated, said terminals being electrically in series with said fixed and moving contacts and the carbon pile.

12. A regulator as in claim 11 in which the fixed and moving contacts are of small area.

13. An electrical regulator comprising a carbon pile, terminals by which the regulator is con-

nectible to a circuit to be regulated, said carbon pile being in series with said terminals, fixed means engaging one end of the carbon pile, means responsive to the differential action of a spring 5 and an electromagnet for exerting pressure on the other end of the pile, and means having separable contacts interposed between the ends of the carbon pile and the means in engagement therewith, said separable contacts being in series with the pile and between it and said terminals and being mounted to vibrate like the vibratory contacts of a Tirrill type regulator in response to external vibrations acting axially of the carbon pile.

FREDERICK NEWTON.
